COMBINED BOW AND ANCHOR LAMP

Peter E. Brady, Willowdale, Ontario, Canada, assignor
to Dominion Auto Accessories Limited, Toronto,
Ontario, Canada

Filed Feb. 2, 1973, Ser. No. 329,183

Term of patent 14 years

Int. Cl. D26—06

U.S. Cl. D48—32 R

FIG. 1

FIG. 2

FIG. 3

FIG. 4

FIG. 1 is a side elevational view of the combined bow and anchor lamp showing my new design.

FIG. 2 is a front elevational view of the same.

FIG. 3 is a rear elevational view of the same.

FIG. 4 is a top view of the same.

The broken lines are shown in FIGS. 1, 2 and 3 for illustrative purposes only.

What I claim is:

The ornamental design of a combined bow and anchor lamp, as shown and described.
